UNITED STATES PATENT OFFICE.

ALEXANDER FORIN, OF EDMONTON, ALBERTA, CANADA.

PEEP SIGHT FOR SHOTGUNS.

Application filed February 9, 1922. Serial No. 535,305.

To all whom it may concern:

Be it known that I, ALEXANDER FORIN, a resident of the city of Edmonton, in the Province of Alberta, Canada, have invented 5 certain new and useful Improvements in Peep Sights for Shotguns, of which the following is the specification.

My invention relates to improvements in peep sights for shot guns and the object 10 of the invention is to devise such a sight which can be readily and quickly attached to the gun. A further object is to construct a peep sight which will be adapted to be applicable to single barrel or double barrel 15 guns.

My invention consists of a peep sight constructed and arranged all as hereinafter more particularly described and illustrated in the accompanying drawing in which:

20 Fig. 1 represents a side view of a double barrel shot gun showing my sight applied thereto.

Fig. 2 is a cross sectional view of the barrels of the gun showing my device applied 25 thereto.

Fig. 3 is a detail of the sight,

Fig. 4 is a cross sectional view of the barrel of a shot gun showing my device applied thereto and

30 Fig. 5 is a detail of the particular construction of sight applicable to single barrel guns.

Like characters of reference indicate corresponding parts in the different views.

35 1 is the gun. 2 are the barrels thereof. 3 is the hand grip. My peep sight is preferably constructed with an open sight portion of substantially inverted U-shape and with opposingly bowed portions 5 preferably 40 formed integrally with the portion 4. 6 is a spring suitably secured to the extremity of one of the portions 5 and provided with the looped free end 7 adapted to hook over the hook-shaped extremity 8 of the other bowed 45 portion 5 when the sight is applied to the gun.

From the above description and on reference to the drawings it will be seen that the only difference between the different types of sights for double and single barrelled guns is the variation of the bow members 5 to conform with the shapes of the single barrel or the double barrel as the case may be, it being understood that the sight is applied to the gun as illustrated in Figure 1 55 and that the bowed portions 5 conform in shape with the part of the barrels they engage.

The spring 6 is then extended until it is possible to hook the end 7 over the hook 8 60 when the sight will be held in place on the gun.

In order to remove the same it is merely necessary to unhook the spring.

From the above description it will be seen 65 that I have devised a simple and effective peep sight for shot guns that can be removed therefrom and is designed to be used in conjunction with the ordinary foresight 9.

What I claim as my invention is:

1. A peep sight for shot guns comprising a wire bent into inverted U-shape and adapted to straddle the barrel of the gun, the central portion of said wire being bent to form a subsidiary U-shaped portion constituting 75 the peep sight, and resilient means attached to the end of one of the legs of the U-shaped wire and detachably engageable with the end of the other for holding the same in position on the barrel.

2. A peep sight for shot guns comprising a wire bent into inverted U-shape and adapted to straddle the barrel of the gun, the central portion of said wire being bent to form a subsidiary U-shaped portion constituting 85 the peep sight, the extremity of one of the legs of the wire formed into an eye and the extremity of the other leg formed into a hook, a spiral spring attached at one end to the eye and at the other end detachably 90 secured to the hook.

ALEXANDER FORIN.
